UNITED STATES PATENT OFFICE.

JAMES A. CAMERON AND GUSTAF BIRGER BIRCH, OF BROOKLYN, NEW YORK, AS-
SIGNORS TO CAMERON MACHINE COMPANY, OF BROOKLYN, NEW YORK, A COR-
PORATION OF NEW YORK.

WINDING MACHINE.

Application filed July 19, 1923, Serial No. 652,479. Renewed December 17, 1925.

This invention relates to winding machines, and has for its main object and feature a simple and reliable construction for controlling the top pressure roll that acts on the top surface of the wound material in winding machines.

In the accompanying drawings is shown a concrete and preferred form of the invention in which:

10 Fig. 1 is a side elevation of a winding machine, looking in the direction of arrow 1 of Fig. 2.

Fig. 2 is a vertical sectional view on the plane of line 2—2 of Fig. 1.

15 Fig. 3 is a vertical sectional detail view on an enlarged scale on the plane of line 3—3 of Fig. 2.

Fig. 4 is a sectional view on the plane of line 4—4 of Fig. 3.

20 The surface winding drums are indicated at 32 and 33. 34 is the winding shaft, 35 the rewound material and 36 is the top pressure roll. Suitable slitting means may be employed if desired. The top pressure roll

25 is vertically displaceable as the diameter of the rewound material increases and provision must also be made whereby the top pressure roll can be lifted at will to remove the wound material. It is important, however,

30 to keep the two ends of the top pressure roll in parallelism as far as possible so as to maintain, as nearly as possible, a uniform diameter of the wound material at both ends. To accomplish this and other purposes there

35 is provided a carriage 37 sliding on guides 38 of the framework, which guides are provided with stationary vertical racks 39, and mounted on carriage 37 is a pinion shaft 40

carrying pinions 41 engaging racks 39. Rotation of said pinions is caused by dragging

40 them across the face of the racks either by displacement of the carriage or by other means presently to be described. Carriage 37 is suspended on flexible connections 42

45 passing over rotatable members or sprockets 43 and is counterbalanced by weights 44 sliding on ways 45. It will be seen that the center of pinion shaft 40 is, preferably, almost in vertical alinement with the center

50 of the top pressure roll so that possible binding effect of the parts is obviated. Each sprocket is, preferably, mounted on an independent or individual stud shaft 46, this being advantageous because if chains 42, or

parts thereof, should stretch unevenly they 55 would exert unequal pull at opposite sides of the machine and thus tend to interfere with the equalizing action of pinion shaft 40 and pinions 41 engaging racks 39.

The transmission means for raising or 60 lowering the top pressure roll at will is preferably constructed as follows: Carried by one of the sprockets 43 is a ratchet 47 and engaging with this ratchet is a pawl 48, said pawl being mounted on gear 49. Both 65 sprockets 43 have roller bearings 50 so as to rotate easily on the stud shafts. Gear 49 is mounted loosely on one of said stud shafts and meshes with another gear 51 carrying sprocket 52. Passing over this sprocket 52 is 70 a flexible connection 53 also engaging a sprocket 54 in the lower part of the machine. 55 is an idler interposed in the path of connection 53. Mounted to move with sprocket 54 is a ratchet 56 and a handwheel 57. 58 75 indicates a stop pawl engaging ratchet 56.

As the top pressure roll rises in response to the increase in diameter of the wound material sprockets 43 will rotate independently of the back gearing or transmission means 80 controlled by handwheel 57. In other words: Said transmission means are unresponsive to the turning movements of rotatable members 43. On the other hand by manipulating the transmission means members 43 will be actuated, that is: one of said members will be actuated thereby lifting the pressure roll and pinion shaft, and this, in turn, will rotate the other member 43. When lowering carriage 37 pawl 48 must be disengaged from ratchet 47. 85 90

We claim:

1. Controlling means for top pressure roll in winding machines comprising: a vertically displaceable top pressure roll, vertically extending stationary racks, a pinion shaft, displaceable with said top pressure roll, the axis of which is substantially in vertical alinement with that of said top pressure roll, pinions, on said pinion shaft, in engagement with said racks, and means for raising and lowering said top pressure roll and pinion shaft to thereby cause rotation of the pinions in engagement with the racks. 95 100

2. Controlling means for top pressure roll in winding machines comprising: a vertically displaceable top pressure roll, vertically extending stationary racks, a pinion shaft 105

displaceable with said top pressure roll, the axis of which is substantially in vertical alinement with that of said top pressure roll, pinions, on said pinion shaft, in engagement with said racks, and flexible connections, controlled from a fixed center of rotation, for raising and lowering the top pressure roll and pinion shaft to thereby cause rotation of the pinions in engagement with the

10 racks.

3. Controlling means for top pressure roll in winding machines including: a vertically displaceable top pressure roll, flexible connections connected at one end with the top

15 pressure roll and weighted at their other end, rotatable members to be actuated by and over which said flexible connections pass, and transmission means, unresponsive to turning movement of the rotatable members, 20 which, when actuated, serve to turn the rotatable members and thereby to lift the top pressure roll.

4. Controlling means for top pressure roll in winding machines including: a vertically 25 displaceable top pressure roll, flexible connections connected at one end with the top pressure roll and weighted at their other end, rotatable members to be actuated by and over which said flexible connections pass, 30 and transmission means including a ratchet and pawl, unresponsive to turning movement of the rotatable members, which, when actuated, serve to turn the rotatable members and thereby to lift the top pressure roll.

35 5. Controlling means for top pressure roll in winding machines including: a vertically displaceable top pressure roll, flexible connections connected at one end with the top pressure roll and weighted at their other end, 40 independently mounted rotatable members to be actuated by and over which said flexible connections pass, and transmission means, unresponsive to turning movement of the rotatable members, which, when actuated, 45 serve to turn the rotatable members and thereby to lift the top pressure roll.

6. Controlling means for top pressure roll in winding machines including: a vertically displaceable top pressure roll, flexible con-

nections connected at one end with the top pressure roll and weighted at their other end, independently mounted rotatable members to be actuated by and over which said flexible connections pass, vertically extending stationary racks, a pinion shaft displaceable with said top pressure roll, pinions, on said pinion shaft, in engagement with said racks, and transmission means, unresponsive to turning movement of the rotatable members, which, when actuated, serve to turn one of the rotatable members and thereby to lift the top pressure roll and to turn the other rotatable member.

7. Controlling means for top pressure roll in winding machines including: a vertically displaceable top pressure roll, flexible connections connected at one end with the top pressure roll and weighted at their other end, independently mounted rotatable members to be actuated by and over which said flexible connections pass, and transmission means, including a ratchet and pawl, unresponsive to turning movement of the rotatable members, which, when actuated, serve to turn the rotatable members and thereby to lift the top pressure roll.

8. Controlling means for top pressure roll in winding machines including: a vertically displaceable top pressure roll, flexible connections connected at one end with the top pressure roll and weighted at their other end, independently mounted rotatable members to be actuated by and over which said flexible connections pass, vertically extending stationary racks, a pinion shaft displaceable with said top pressure roll, pinions, on said pinion shaft, in engagement with said racks, and transmission means including a ratchet and pawl, unresponsive to turning movement of the rotatable members, which, when actuated, serve to turn one of the rotatable members and thereby to lift the top pressure roll and to turn the other rotatable member.

Signed at Brooklyn, in the county of Kings and State of New York, this 16 day of July, 1923.

JAMES A. CAMERON.
